UNITED STATES PATENT OFFICE.

EMIL A. PETERSON, OF APPLETON, WISCONSIN, ASSIGNEE TO ERNST MAHLER, OF NEENAH, WISCONSIN.

DOCTOR FOR BEATING ENGINES.

Application filed October 2, 1922. Serial No. 591,879.

To all whom it may concern:

Be it known that I, EMIL A. PETERSON, a citizen of the United States, and resident of Appleton, in the county of Outagamie 5 and State of Wisconsin, have invented new and useful Improvements in Doctors for Beating Engines, of which the following is a description, reference being had to the accompanying drawings, which are a part of 10 this specification.

This invention relates to doctors for beating engines, such as are usually employed in making paper pulp and the like and has for one of its objects to provide a device of this 15 character which will be simple in construction, entirely automatic in its action, and more efficient in operation than those which have been heretofore proposed.

A further object of the invention is to 20 provide a doctor which may be located in an external position in relation to the beating engine roll, to the end that it will be readily accessible and comparatively easy to repair in case of breakage or other damage.

25 In making paper pulp it is customary to subject the stock, composed of fibers and water, to the action of a beating roll, whereby the said fibers may be fully disintegrated and commingled with the water. Such disintegration is accomplished by various 30 means, one example of which is the well known Niagara beater, in which the circumference of the beater roll is provided with a plurality of transverse blades or knives 35 which rotate in close proximity to the bottom of the beater chamber. The stock is compelled to travel between said blades and said bottom and a grinding, tearing, or cutting action is thus had, which results in a 40 comparatively complete disintegration of the fibers.

When such a beater is operating, it happens in many instances, particularly when the machine is being filled with material, 45 that masses of unbeaten stock will be forced completely under the roll without being properly disintegrated. This necessarily causes the beater roll to rise somewhat from its normal position and provision is ordinarily made to accommodate such movements to the beater roll. These reciprocating

movements must, of course, be likewise accommodated by the doctor and it is an important object of the present invention to provide a doctor which will automatically 55 compensate for such rises of the roll.

With the above and other objects in view, which will appear as the description proceeds, the invention consists in the novel 60 details of construction and combinations of parts more fully hereinafter disclosed and particularly pointed out in the appended claims.

Referring to the accompanying drawings in which like numerals designate like parts 65 in all the views:—

Fig. 1 is a fragmentary side elevational view of a so-called Niagara beater with the present invention applied thereto;

Fig. 2 is a plan view of the parts shown 70 in Fig. 1; and

Fig. 3 is a fragmentary vertical sectional view, taken approximately on the plane indicated by the line 3—3 of Fig. 2, looking in 75 the direction of the arrows.

In the said drawings the numeral 5 designates a portion of the frame of a beating engine of any approved type, here illustrated as a Niagara beater, in which frame is journaled the beater roll 6, carried by the 80 shaft 7. The said roll is provided with the usual blades or knives 8, and a housing or cover 9 is placed thereover to prevent the escape of fibers or stock which may adhere to said roll, all as is well known.

The said roll revolves in a counter clockwise direction, as indicated by the arrow in Fig. 3, and it normally discharges the ground paper pulp over the back fall 10, beneath the deflecting arch or cover 11, in 90 the direction of the arrows.

The doctor constituting the present invention may be located at any convenient point, such, for example, as the point where the roll cover 9 joins the deflecting arch 11, (see 95 Fig. 3). The said doctor comprises a shaft or rod 12, extending transversely on the roll 6, and suitably journaled in the side walls 5, of the beater. The said shaft 12 is provided with the tangential finger or extension 13, which likewise extends across the beater and in its normal position its lowermost ex-

tremity is in close proximity to the outer ends of the beater blades 8, as is clearly illustrated in Fig. 3.

The shaft or rod 12 of the doctor extends somewhat beyond the side walls 5 at either end, and is provided with a pair of depending arms 14, (see Figs. 1 and 2) to which are pivotally connected the push rods 15. These push rods are provided with turn-buckles 16, for changing their lengths to adjust the toe 13 of the doctor to and from the blades 8, whereby the clearance between these parts may be controlled at will. The said push rods 15 are also provided with rollers 17 which engage the surface of the shaft 7 as will be clearly seen from the drawings. The said doctor shaft 12 is also provided with an arm or lever 18 which carries a counter weight 19 so disposed as to normally tend to move the toe of the doctor toward the blades 8 of the beater roll.

The operation of the device will be clear from the foregoing but may be briefly summarized as follows:

Supposing the roll 6 to be rotating in a counter clockwise direction, as indicated by the arrow in Fig. 3, and paper stock to be supplied thereto, the said stock after being subjected to the grinding and beating action of the roll 8 will be carried forward and the major portion thereof discharged over the back fall 10. Any fibers or stock which adhere to the blades of the roll and are not discharged over the said back fall, will be carried around until they are engaged by the toe 13 of the doctor 12, which will dislodge them from the said blades 8 and cause them to be carried forward through the passage above the said back fall 10.

As above stated it sometimes happens that masses of fibers are caught beneath the roll, thus causing the same to rise in its bearings in the beater frame. Provision is usually made to accommodate such rises of the roll itself, but if the doctor 12 was rigidly mounted relative to said roll, such a rise of the latter would bring the blades 8 into contact with said doctor, thus causing breakage of either the blades or the doctor, or both.

In order to prevent this, the push rods 15 are provided, engaging the shaft 7 of the roll 6 and when the latter rotate in their normal position, the doctor will be maintained in the position illustrated in Fig. 3. However, should the roll 6 rise in its bearings, such motion will be transferred from its shaft 7 to the push rods 15 and, through the arms 14 will cause a partial rotation of the shaft 12 of the doctor, thus causing the latter to move in a counter clockwise direction, to the dotted position shown in Fig. 3, thereby preventing the blades of the roll from coming in contact therewith. As the roll settles back to its normal position the counter weight 19 will restore the doctor to

the full line position, as will be readily apparent.

While one physical embodiment of the invention has been described and illustrated, it is obvious that those skilled in the art may vary the details of construction, as well as the arrangement of parts, without departing from the spirit of the invention and therefore, it is not wished to be limited to the above disclosure except as may be required by the claims.

What is claimed is:—

1. In a beating engine, a beater roll mounted for rotation and for movement transversely of its axis; oscillatable means for removing fibers from the periphery of said roll; means controlled by, and responsive to, the transverse movements of said roll, for moving said removing means in one direction when said roll rises; and means comprising a lever arm and a weight for moving said removing means in the opposite direction when said roll falls.

2. In a beating engine the combination with a beater roll mounted for rotation and for substantially vertical movement relative to its axis; means comprising a transverse member pivotally mounted adjacent the periphery of said roll, adapted to remove fibers therefrom; arms carried by said transverse means; and connections secured to said arms and engaging the shaft of said roll whereby said transverse member may oscillate as said roll rises and falls; to maintain a predetermined distance between said transverse member and the periphery of said roll.

3. In a beating engine the combination of a beater roll provided with a plurality of transverse blades upon its periphery, said roll being mounted for rotation and for substantially vertical movements; a transverse member pivotally mounted adjacent the outer extremities of said blades and adapted to remove fibers therefrom; arms carried by said transverse member; adjustable connections secured to said arms and engaging the shaft of said roll whereby said transverse member may oscillate about its pivots in response to the rise and fall of said roll, to maintain a predetermined distance between said member and the extremities of said blades; and a counter weight secured to said transverse member for moving the latter in one direction.

4. In a beating engine provided with a beater roll mounted for rotation and for substantially vertical movements and with a discharge passage, the combination of a transverse member pivotally mounted adjacent the periphery of said roll, adapted to remove fibers therefrom and to discharge the same into said passage; arms carried by said transverse member; push rods pivotally secured to said arms and engaging the

shaft of said roll whereby said transverse member may move in one direction when said roll rises to maintain a predetermined distance between said member and the periphery of said roll; a counter weight secured to said transverse member adapted to move the latter in the opposite direction when said roll falls, and means for adjust-

ing the lengths of said push rods to control the predetermined distance between said transverse member and the periphery of said roll. ¹⁰

In testimony whereof, I affix my signature.

EMIL A. PETERSON.
